(57) **CLAIM**

The ornamental design for a charging stand for a robot, as shown and described.

DESCRIPTION

FIG. 1 is a front, right perspective view of a charging stand for a robot in accordance with our new design; FIG. 2 is a front elevation view thereof; FIG. 3 is a rear elevation view thereof; FIG. 4 is top plan view thereof; FIG. 5 is a bottom plan view thereof; FIG. 6 is a right-side elevation view thereof; FIG. 7 is a left-side elevation view thereof; FIG. 8 is a left, rear perspective view thereof; FIG. 9 is a bottom, left perspective view thereof; FIG. 10 is a front, right perspective view thereof, showing a robot in broken lines; and, FIG. 11 is a rear, right perspective view thereof, showing a robot in broken lines.

The broken lines shown in the drawings are for the purpose of illustrating unclaimed portions of the charging stand for a robot, or environmental structure, and form no part of the claimed design.
